UNITED STATES PATENT OFFICE.

WILLIAM H. MINER, OF CHICAGO, ILLINOIS.

MACHINE FOR TESTING AND REGISTERING THE ACTION OF DRAFT-RIGGING.

1,137,999.

Specification of Letters Patent.

Patented May 4, 1915.

Application filed July 7, 1913. Serial No. 777,610.

To all whom it may concern:

Be it known that I, WILLIAM H. MINER, a citizen of the United States, residing at Chicago, in the county of Cook and State of Illinois, have invented a certain new and useful Improvement in Machines for Testing and Registering the Action of Draft-Rigging, of which the following is a full, clear, concise, and exact description, reference being had to the accompanying drawings, forming a part of this specification.

My invention relates to machines for testing and registering the action of draft rigging.

15 The object of my invention is to provide a machine of simple construction for accurately testing and recording the action of draft rigging for railway cars.

The machine embodying my invention 20 comprises in coöperative combination a bumping post, a recording device mounted independently of the bumping post and having a revoluble disk, means for revolving the same, a marker for the disk, and 25 means for actuating the marker adapted to engage a railroad car and be given motion thereby; a pocket secured to the bumping post to receive a draft gear, and a railroad car provided with a pocket to receive a draft 30 gear in a position opposed to the draft gear mounted in the pocket of the bumping post so that as the car approaches the bumping post the draft gears to be tested are mounted upon the bumping post and car under 35 conditions closely simulating the conditions of actual service, and upon such approach the means for actuating the marker are engaged by the car so that the change in the speed of the car and the effect of the 40 draft gears thereon may be accurately recorded by the marker upon the disk, which meanwhile is revolving at a uniform rate of speed.

In the accompanying drawings forming 45 a part of this specification—Figure 1 is a side elevation of a machine embodying my invention, showing the recording device in longitudinal section; Fig. 2 is a plan view of the recording device; Fig. 3 is an end 50 view of the bumper post, the recording device and the bridge therefor; Fig. 4 is a plan view of a hoisting device and the upper end of an inclined track used in connection with my device; Fig. 5 is a side elevation 55 thereof; Fig. 6 is a plan view of the lower end of said track showing a railroad car in

conjunction with my device; Fig. 7 is a side elevation thereof.

In the drawings 8 represents a bumper post, which may be of any suitable design, 60 and mounted upon a railroad track 9. The recording device 10 is mounted independently of the bumper post, preferably upon a bridge 11, the piers 12, 12 of which are stationed firmly at either side of the railroad track, and preferably outside of the area surrounding the bumper post, subject to upheaval of ballast when a car engages the bumper post, so as to prevent communication of jars from the bumper post to the said 65 piers. A pocket 13 open at its forward end to receive a draft gear is rigidly mounted to the forward face of the bumper post, and at the standard height above the track obtaining in railroad practice. The said 70 pocket is provided with a longitudinal way 14 to receive the angular arm 15 of a follower 16.

17 represents a draft gear to be tested mounted within the pocket 13 of the bumper 80 post.

18 represents an opposed draft gear to be tested, the same being mounted at the standard distance above the track in the pocket 19, which is rigidly secured to the 85 end 20 of the railroad car 21. The pockets 13 and 19 each are provided with means for rigidly securing the gears to be tested, preferably the slot 22, in the pocket on the car with a key 23 passing therethrough, and a 90 similar slot 24 and key 25 in the pocket 13 upon the bumper post.

The follower 16 is arranged to be received between the ends of the gears to be tested, and moves between the same, the angular 95 arm 15 being in sliding engagement with the guide or way 14 in the pocket 13 upon the bumper post.

The recording device 10 comprises a frame 26 having a base 27 secured to the bridge 11, 100 preferably by the bolts 28, 28. Extended upwardly at the forward portion of the base 27 is provided the forward arm 29 having the longitudinal perforation 30 therein. Upwardly extended from the rear of the base 27 is provided the rear arm 31 having the longitudinal perforation 32 in alignment with the perforation 30 of the forward arm 29, the perforation 32 terminating in a recess 33. A bar 34 passes through the 105 perforation 30 in the front arm 29, and through the perforation in the rear arm 110

entering the recess 33 in said arm, the recess 33 having mounted therein a spring 35 set at its forward end against the bar 34 and at its rearward end against the screw 36, by means of which the tension of the spring 35 may be suitably adjusted.

The forward arm 29 and rearward arm 31 of the recording device are in preferable construction integral with the cup-like member 37 within which the revolving disk hereinafter described is seated. Between the forward arm 29 and the rear arm 31 is mounted a revoluble disk 38 having a central vertical shaft 39, which may be driven 10 by any suitable means, preferably a spring mechanism within the box 40.

In preferable construction arms 41 are secured to each side of the box 40, each of said arms being provided at its upper end with 20 a roller 42 engaging the under-face of the disk 38.

Mounted on the bar 34 between the arms 29 and 31 is the marker 43, consisting preferably of a sleeve 44, a set screw 45 to secure 25 the same at any point upon the bar, and pivoted to said sleeve a holder 46 for the pencil 47.

The front end of the bar 34 is adapted to engage a buffer 48 adjustably mounted 30 within the bracket 49, which is secured to the forward end 20 of the car 21 by any suitable means, preferably the bolts 50, the said bracket being provided with a set screw 51 adapted to secure the buffer 48 at 35 any desired distance from the end of the car. The buffer 48 may be advanced to a position and the bar 34 may be secured in a position by means of the sleeve 52 and the set screws 53 thus engaging the 40 inner face of the front arm 29 of the recording device so that the buffer 48 and the bar 34 meet simultaneously with the meeting of the ends of the opposed gears in the pocket 13 of the bumper post and the pocket 45 19 upon the car respectively.

A disk 55, preferably of smooth paper or any similar material, is mounted upon the revoluble disk 38. The disk 55 is provided with concentric circles of equal spacing from 50 each other. As for instance a selected radius of the outer circle will be crossed by the other circles at points thereon one-eighth of one inch apart, as illustrated by the lines 56-56 in Fig. 2 of the drawings. The said disk 55 is also provided with equally spaced radial lines 57-57.

To facilitate the use of the recording device I provide a jib crane 58 near the bumper post to handle the draft gears in mounting 60 them in and removing them from the pockets upon the car and bumper post. I also provide a larger crane 59, preferably equipped with a magnet hoist to facilitate a variable loading of the car, the weight of which may 65 be determined by a car scale 60. The rail-

road track 9 is inclined for a portion of its length, as illustrated in Figs. 4 and 5 of the drawings, and at the end of said track is stationed a hoisting plant 60 by means of which and the cable 61 with the truck 62 the 70 car 21 may be drawn to any point upon the inclined track to give a predetermined velocity to the same as it approaches the bumper post when released.

In making a test the draft gears to be 75 tested are mounted one in the pocket 19 of the car 21 and one in the pocket 13. The bumper post 8, the bar 34 if the recording device to which the pencil is attached and the buffer 48 upon the car are so adjusted 80 that as the car nears the bumper post in its approach thereto they meet approximately simultaneously with the meeting of the opposed ends of the draft gear, the object being to record on the disk 55 through the diagram described thereon by a moving pencil 85 engaging the uniformly revolving disk, the velocity of the car at the time of the engagement of the opposing gears, and the actual reduction of the velocity up until the time it 90 is brought to a full stop. Also with the disk revolving at a uniform rate the speed and character of the recoil is also indicated on the diagram. The angle of velocity being constant the speed can be determined at any 95 point during the period of retardation. For instance if the chart or disk 55 were revolved at the rate of thirty revolutions per minute it would pass through one degree in one one hundred and eightieth of a second. If the pencil should be advanced a radial distance of one inch while the chart 100 revolves one degree it would record a velocity of approximately ten miles per hour, or if the pencil advanced a radial distance of 105 one inch while the chart revolves a distance of two degrees it would record a velocity of substantially five miles per hour.

A study of the variation of the time element involved with the deceleration curve 110 made by the pencil will illustrate the exact mechanical action of draft gears in performing their function of absorbing shock. The disk 55 may be removed after each test and a new one placed upon the revoluble disk 38, 115 and the curve described by the pencil upon the chart may be then plotted upon a rectangular diagram to graphically indicate the shock absorbing value, and the speed of retardation of cars by gears subjected to this 120 test.

I claim:

1. In a device of the character described, in combination, a bumper post, a car, means upon the bumper post and means upon the 125 car to hold draft gears in opposed relation, a recording device located adjacent the bumping post, the said recording device comprising a revoluble disk, a marker for the same and a bar to actuate said marker, 130

and means upon the car adapted to engage said bar whereby the marker is operated by the moving car while said disk is revolving and the gears are in engagement with each other.

- 5 2. In a device of the character described, a railroad car, a pocket thereon adapted to receive a draft gear, a bumper post, a pocket thereon adapted to receive a draft gear, a 10 recording device mounted independently of the bumper post, said recording device being provided with a revolving disk, a marker therefor, and a bar adapted to be actuated by a car and to actuate said marker.
- 15 3. In a device of the character described, a railroad car, a pocket thereon to receive a draft gear, a bumper post, a pocket thereon to receive a draft gear, a follower supported by said last mentioned pocket and in sliding 20 engagement therein, a revolute disk, means for revolving the same, a marker for said disk, a bar to actuate said marker, and means upon the said car for actuating the said bar at a predetermined time in reference to the 25 engagement of two draft gears when placed in the said pockets.

4. In a device of the character described, an inclined track, a car adapted to operate thereon, means upon said car to secure a

draft gear, a bumper post associated with 30 said track, means thereon to secure a draft gear in opposed relation to the first mentioned draft gear, a revolute disk mounted independently of the said bumper post, means for revolving said disk, a marker for 35 the said disk, a bar for actuating said marker, a buffer on the said car adapted to engage the said bar, whereby the rate of travel of the car upon engagement of the opposed draft gears may be recorded by said 40 marker on said revolute disk.

5. In a device of the character described, in combination a bumper post having means thereon to hold a draft gear in alinement with another draft gear carried by a car, a 45 recording device including a movable element located adjacent the bumper post and a marker adapted to mark on said movable element, the marker being movable in a line parallel with the center line of a draft gear 50 carried by the bumper post, and means for operating said marker from a car when a car is moved toward the bumper post.
